TAPPING DOLL

Berl Field, 122 N. Washington, Dimondale, Mich.

Filed Sept. 24, 1962, Ser. No. 71,818

Term of patent 14 years

(Cl. D34—15)

FIG. 1

FIG. 2

FIG. 3

FIGURE 1 is a side perspective view of a tapping doll, showing my new design as it appears when in a tapping position;

FIGURE 2 is a front elevation view of the tapping doll as it appears in stationary position; and

FIGURE 3 is a side elevation thereof, the side opposite thereto being a mirror image thereof.

I claim:

The ornamental design for a tapping doll, as shown and described.
